US00D653119S

(12) **United States Design Patent**
Hunter et al.

(10) **Patent No.:** **US D653,119 S**
(45) **Date of Patent:** **** Jan. 31, 2012**

(54) **PLASTIC CONTAINER**

(75) Inventors: **Travis A. Hunter**, Hellam, PA (US);
Raymond A. Pritchett, Jr., Manchester,
PA (US)

(73) Assignee: **Graham Packaging Company, L.P.**,
York, PA (US)

(**) Term: **14 Years**

(21) Appl. No.: **29/388,558**

(22) Filed: **Mar. 30, 2011**

(51) LOC (9) Cl. **09-01**

(52) U.S. Cl. **D9/560**; D9/569; D9/574

(58) **Field of Classification Search** D9/682,

(57) **CLAIM**

The ornamental design for a plastic container, as shown and described.

DESCRIPTION

FIG. 1 is a top, front, right side perspective view of a plastic container showing our new design;
FIG. 2 is a bottom, front, right side perspective view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top plan view thereof; and,
FIG. 8 is a bottom plan view thereof.

The dash-dash-dash broken lines shown in the drawings are included for the purpose of illustrating environmental structure and form no part of the claimed design.

1 Claim, 5 Drawing Sheets
